UNITED STATES PATENT OFFICE.

ALFRED T. NEWELL, OF BIRMINGHAM, ALABAMA.

ROADWAY.

Application filed May 31, 1921. Serial No. 473,698.

To all whom it may concern:

Be it known that I, ALFRED T. NEWELL, a citizen of the United States, residing at Birmingham, in the county of Jefferson and 5 State of Alabama, have invented certain new and useful Improvements in Roadways, of which the following is a specification.

This invention relates to paving, and especially to a concrete paving or road, distinguished by novelty in particulars herein- 10 after pointed out.

Common methods of building roads at present include so-called brick roads, in which a great number of small bricks or 15 blocks are laid on a prepared bed or foundation either with or without intervening cement or adhesive material. The objection to this type of road arises from the cost of laying the same, since manual labor has to be 20 employed in setting the bricks or blocks in place as well as in constructing curbings and gutters at the sides. A further objection arises from the large number of joints which 25 permit water to leak thru and either undermine the sections of the road or disintegrate the same from the effect of frost. Further objections to so-called brick roads are 30 known to road builders, but the roughness of said roads after a certain amount of wear may be mentioned.

Another common road is the so-called concrete road in which a layer of concrete is placed on a bed, the concrete being mixed and molded as the work progresses, at or 35 adjacent to the place where it is laid. This requires a portable mixing outfit and also erection of forms at the sides. Such roads wear comparatively well, but are costly, and are very subject to cracking which lets in 40 frost and makes bad breaks by the pounding of the traffic on the cracks.

The object of the present invention is to 45 avoid the objections incident to the foregoing and other types of roads, and it embodies the production or formation of relatively large concrete slabs, which may be constructed at a plant somewhat distant from the place where they are laid and transported by power devices, the slabs being 50 so large that only a few joints are formed and being of such weight and area that small sections thereof are not apt to collapse or be undermined, as with brick roads.

55 It is intended that the road shall preferably consist of two lines of slabs, of sufficient

width to meet at the middle line of the road and sufficient length to avoid a great many transverse joints. These slabs are fitted together and interlocked by concrete dowels 60 or dovetails, and each slab shall be reinforced by metal bars embedded therein, some of the bars being so located as to assist in forming and strengthening the bonds at the joints. A further feature of the structure 65 is that the curbing and gutters are produced at the outer edge of the slabs, and no separate parts for these are necessary. A further feature of the invention is that the transverse joints are on diagonal lines across 70 the road so that vehicle wheels strike the joint one at a time. Other features of the invention will be apparent from the following description and the accompanying drawings in which Fig. 1 is a plan of the road 75 constructed of the slabs. Fig. 2 is a side edge elevation of one of the slabs. Fig. 3 is an end elevation at the middle line. Fig. 4 is a bottom plan of one of the slabs.

As stated, these slabs will preferably be 80 made of concrete at a central plant and each slab may weigh a ton or more. They will be transported to the location and laid by means of power derricks or the like. The top surface 6 of each slab is of sufficient 85 width to cover one-half the width of the road, that is from the curb line to the middle line, and in order to form the crown of the road the slab is made thicker at the inner end or middle line, and terminating in a 90 gutter 7 and a curb 8, thus producing all these parts in a single slab.

The bottom of the slab is provided with a plurality of grooves 9 which extend substantially cross-wise of the road, and when 95 the slabs are laid on a prepared bed the ribs between the grooves will sink into the bed and form a bond therewith, which will tend to prevent side shift of the slabs.

An important feature of the present improvement is that the slabs are formed with oblique angles, the ends of the slabs being parallel with the line of the road while the sides of the slab are at an oblique angle thereto, similar to the slabs described in 100 the former application, but with this improvement, that in the present invention the inclination of the side lines is backwardly from the curb line to the middle line. Stated in other words, the slabs which are 105 laid on the right hand half or side of the road incline backwardly toward the middle

of the road. This has the effect that under the thrust of traction, which as a rule will follow the right hand side of the road, the angular thrust of the slabs will have a tendency to shift the slabs inwardly toward the middle line, instead of outwardly toward the curb, consequently the road traction will tend to keep the ends of the slabs together at the middle line and to prevent separation 5 at the joints. This manner of constructing and laying the slabs also has the advantage that it will tend to prevent skidding, since the joints at the side edges 10 will tend to throw a vehicle toward the crown or middle 15 line, and this will be of particular advantage when the roadway is wet or slippery.

A further improvement in the present invention consists in the manner of making the joints or bonds between the slabs. These 20 joints are made by dove-tailed or undercut recesses 11 at the corners of the slabs, so at the middle line the corners of four slabs meet, and are joined by means of concrete poured in the cross-shaped recesses so produced, as indicated at 12, and at the curb line two of the recesses are connected by concrete bonds poured in as indicated at 13. This manner of bonding the slabs I consider 25 superior to the recesses in the sides as shown 30 in the former application.

When the slabs are molded a sufficient or desired number of reinforcing bars or rods will be imbedded therein, some of which are indicated at 14, and, preferably, some of these bars will extend across the recesses 11, as shown at 15, so that they will be seized or engaged by the bonds poured in the recesses 11, thereby assisting in strengthening the bonds and locking the slabs together. Before 40 being bonded the slabs can be wired together securely, by wires 17, thus forming a metallic tie as well as a concrete bond.

The reinforcing bars exposed at these recesses will also be of advantage in handling 45 and laying the slabs. As stated, they will preferably be handled by power derricks or the like erected on traction vehicles, and the hooks of the derricks may be hooked into the bars exposed at the recesses 11 and so lifted 50 and deposited in the particular place where they are to be laid, the hooks being engaged with the bars in the recesses so that the slabs can be drawn up close together by the power devices before the hooks are disengaged, 55 with little or no necessity for manual shifting.

After the slabs are laid concrete or the like will be run into the recesses 11 to form the bonds, and the joints between the slabs will 60 preferably be filled with pitch, tar or similar substance, which will act as expansion joints, and the entire surface of the slabs will preferably be covered with a coating of the same or other bituminous material to 65 form a water proof surface.

A roadway constructed of large slabs as above indicated will have the advantage that it is not liable to disintegration in consequence of frost, nor to the formation of holes or pockets, the slabs being of such large 70 area that small or local settlements or pockets in the bed will not result in any surface changes or disturbance, as often occurs in roads made of relatively small bricks or blocks. The road will have all the advantages of a permanent highway without the disadvantages incident to cracking or irregular breaks commonly met with in concrete roadways. 75

The manner of laying the slabs so that 80 traction along the right hand side of the road will tend to shift the slabs toward the middle or crown of the road has manifest advantages, as referred to above, as the slabs will press toward each other both at 85 the middle line and at the transverse joints and this action is assisted by the inclination of the ribs between the grooves 9 on the bottom of the slabs. The constant tendency, therefore, is for the slabs to maintain tight 90 joints with each other.

The invention is not limited to the particular form shown, but obviously many changes may be made within the scope of the following claims. 95

I claim:

1. A roadway consisting of slabs of an area sufficiently large to extend from the crown of the road to the edge thereof, the side edges of the slabs extending obliquely 100 across the road and inclining backwardly from the edge of the road toward the middle line thereof.

2. A roadway consisting of slabs of an area sufficiently large to extend from the 105 crown of the road to the edge thereof, the side edges of the slabs extending obliquely across the road and inclining backwardly from the right edge of the road toward the middle line thereof. 110

3. A roadway consisting of two rows of slabs, each slab of each row extending from the middle line of the road to the edge thereof, the side edges of the slabs extending obliquely across the road and inclining 115 backwardly from the right edge of the road toward the middle line thereof.

4. A roadway consisting of concrete slabs of large area, the inner and outer edges of each slab being parallel to the line 120 of the road and the side edges of the slabs being oblique to said line, whereby the transverse joints between the slabs extend obliquely across the road, said joints inclining backwardly from the right hand edge 125 of the road toward the middle line thereof.

5. A roadway consisting of concrete slabs laid in rows along the road, the corners of the slabs having recesses, and bonds in said recesses, between the slabs. 130

6. A roadway consisting of concrete slabs, each slab being of sufficient size to extend from the middle line of the road to the edge thereof, the meeting corners of the slabs 5 having registering recesses, and bonds in said recesses, between the slabs. 65
7. A concrete paving slab having ribs and grooves in the under side thereof adapted to interlock with the roadbed, said ribs and 10 grooves extending obliquely across the bed and being inclined backwardly from the right hand edge of the slab toward the left hand edge. 75
8. A concrete paving slab of sufficient area 15 to extend from the middle line to the curb line of a roadbed, said slab having oblique angles and inner and outer edges parallel to the middle line, and grooves in the under side of the slab extending backwardly at an angle 20 from the outer edge to the inner edge. 80
9. A roadway consisting of concrete slabs having registering recesses in their meeting edges, reinforcing bars extending across said recesses, ties connecting the bars of adjacent 25 slabs, and bonds in said recesses, between the slabs. 85
10. A roadway consisting of preformed concrete slabs of an area sufficiently large to extend from the crown of the road to the 30 edge thereof, the slab increasing in thickness from the outer to the inner edge, whereby the crown is formed. 90
11. A roadway consisting of preformed concrete slabs laid in two rows, each slab of 35 each row extending from the middle line of the road to the respective edge thereof and decreasing in thickness from the middle line to the edge, whereby the crown is formed. 100
12. A roadway consisting of preformed 40 concrete slabs laid in two rows, each slab of each row extending from the middle line of the road to the respective edge thereof and decreasing in thickness from the middle line to the edge, whereby the crown is formed, 45 and the side edges of the slabs extending obliquely across the road. 105
13. A preformed concrete roadway slab of sufficient size to extend from the middle of the road to the edge thereof and capable of 50 vehicular transportation from the place where made to the place where laid, said slab having a level bottom adapted to be laid on a flat roadbed, and a cambered top surface forming a part of the crown of the roadway, 55 and also having means at its edges whereby it may be tied to adjacent slabs. 110
14. A roadway consisting of preformed concrete slabs laid in two rows, each slab of each row extending from the middle line of 60 the road to the respective edge thereof and decreasing in thickness from the middle line to the edge, whereby the crown is formed, and each slab having a curb formed integral therewith at the outer edge thereof. 115
15. A roadway consisting of preformed concrete slabs of large area, laid in rows along the road, each slab decreasing in thickness from its inner edge to its outer edge, the meeting edges of the slabs having recesses, and bonds in said recesses, between the slabs. 70 120
16. A roadway of preformed concrete slabs, each slab being of sufficient size to extend from the middle line of the road to the edge thereof, the abutting edges of the slabs having registering recesses, and bonds in said recesses, between the slabs. 75
17. A paving concrete slab having a curb formed integral therewith and increasing in thickness from the curb edge to the opposite edge. 80
18. A concrete paving slab having parallel end edges adapted to lie parallel with the middle line of the road and other parallel side edges at an oblique angle to said edges, said slab decreasing in thickness from the inner end edge to the outer end edge. 85
19. A concrete paving slab having recesses at its edges adapted to register with recesses in adjacent slabs, and reinforcements in said slabs exposed at said recesses within the outer line of the edge of the slab for engagement with bonds placed in said recesses. 90
20. A concrete paving slab having ribs and grooves in the under side thereof adapted to interlock with the road bed, said ribs and 95 grooves extending entirely across the slab. 100
21. A concrete paving slab of sufficient area to extend from the middle line to the curb line of a road bed, said slab having oblique angles, and inner and outer edges parallel to the middle line, and grooves in the under side of the slab at oblique angles to said edges. 105
22. A roadway consisting of preformed concrete slabs the edges of which form oblique angles to each other, the slabs being of sufficient area to extend from the middle line of the road to the curb line and of decreasing thickness from the said middle line to the curb line, said slabs when laid forming 110 a joint at the middle line of the road and diagonal transverse joints, and interlocking bonds between the slabs at said joints. 115
23. A concrete roadway paving slab having a level bottom adapted to be laid on a flat roadbed, and a top surface cambered from the inner end to the outer or gutter end and thereby forming a part of the crown of the roadway, the bottom surface having grooves extending from the inner to the outer 120 ends. 120

In testimony whereof, I affix my signature in presence of two witnesses.

ALFRED T. NEWELL.
